DESIGN FOR A PORTABLE ELECTRIC SOUND TRANSMITTER

Joseph R. Cubert, Chicago, Ill., assignor to Aurex
Corporation, Chicago, Ill., a corporation of Illi-
nois

Application March 29, 1940, Serial No. 91,341

Term of patent 3½ years

To whom it may concern:

Be it known that I, Joseph R. Cubert, a citizen
of the United States, and resident of Chicago, in
the county of Cook and State of Illinois, have
invented a new, original, and ornamental Design
for a Portable Electric Sound Transmitter, of
which the following is a specification, reference
being had to the accompanying drawing, forming
a part thereof.

Fig. 1 is a perspective view of the portable

electric sound transmitter, showing my new de-
sign.

Fig. 2 is a side elevational view.

Fig. 3 is an end elevational view of what is
shown in Fig. 1 of the drawing.

Fig. 4 is a plan view thereof.

I claim:

The ornamental design for a portable electric
sound transmitter, as shown.

JOSEPH R. CUBERT.
